Primary Examiner — Kimberly Barnes

CLAIM

(57) The ornamental design for a base station for cleaning robot as shown and described.

DESCRIPTION

FIG. 1.1 is a perspective view of a base station for cleaning robot according to the present design;

FIG. 1.2 is a front view thereof;

FIG. 1.3 is a rear view thereof;

FIG. 1.4 is a left side view thereof;

FIG. 1.5 is a right side view thereof;

FIG. 1.6 is a top view thereof;

FIG. 1.7 is a bottom view thereof; and

FIG. 1.8 is another perspective view thereof.

Broken lines in the drawings illustrate parts of the article and form no part of the claimed design.

1 Claim, 8 Drawing Sheets
